UNITED STATES PATENT OFFICE

LAYTON EUGENE CROE, OF KALAMAZOO, MICHIGAN

DESIGN FOR A SPECTACLE FRAME

Application filed October 27, 1930. Serial No. 37,396. Term of patent 14 years.

To all whom it may concern:

Be it known that I, LAYTON EUGENE CROE, a citizen of the United States, residing at Kalamazoo, in the county of Kalamazoo and State of Michigan, have invented a new, original, and ornamental Design for Spectacle Frame, of which the following is a specification, reference being had to the accompanying drawings, forming part thereof.

Fig. 1 is a rear view of the spectacle frame with the bows collapsed, and

Fig. 2 is a side elevation with the bows open, showing my new design.

The dominant feature of the design is the contour and arrangement of the temple bows for ornamental effect.

I claim:

The ornamental design for a spectacle frame, as shown and described.

LAYTON EUGENE CROE.
